United States Patent Office

Des. 189,123
Patented Nov. 1, 1960

189,123

STUFFED FOOD PRODUCT

Milton L. Brandt, 2637 Garfield St., San Mateo, Calif., and Walter M. Zolezzi, 1435 Francisco St., San Francisco, Calif.

Filed Apr. 15, 1960, Ser. No. 60,214

Term of patent 14 years

(Cl. D82—2)

FIG. 1

We claim:

The ornamental design for a stuffed food product, substantially as shown.
